LUBRICATOR, FILTER, AND REGULATOR UNIT

Robert E. Becker, Logansport, Ind., assignor to Logansport Machine Co., Inc., Logansport, Ind., a corporation of Indiana

Filed Aug. 7, 1958, Ser. No. 52,086

Term of patent 14 years

(Cl. D52—6)

FIG. 3.

FIG. 4.

The rear of the lubricator, filter and regulator unit is plain in appearance.

I claim:

The ornamental design for a lubricator, filter and regulator unit, as shown and described.
